TUNNEL KILN CONSTRUCTION AND
METHOD OF OPERATIONPhilip d'Huc Dressler, Pittsburgh, Pa., assignor to
Swindell Dressler Corporation, Pittsburgh, Pa.,
a corporation of Pennsylvania

Application July 17, 1937, Serial No. 154,179

6 Claims. (Cl. 25—142)

The general object of the present invention is to provide improvements in the construction and the method of operating a continuous tunnel kiln, whereby the heating of the portions of the goods 5 moving through the kiln at different levels may be sufficiently uniform.

In the operation of an ordinary continuous tunnel kiln, including an elongated horizontal goods space through which the goods are moved 10 from one end of the kiln to the other, and having a high temperature heating section intermediate the ends of the kiln, there is a strong tendency to heat goods moving through the goods space at an upper level more highly than the goods moving 15 through the space at a lower level are heated. To prevent or minimize such nonuniformity in heating at different levels, various kiln atmosphere recirculating means and other special expedients, complicating the construction or operation 20 of the kiln, have been used, or proposed, to equalize the goods heating at different levels.

In accordance with the present invention, an approximation to uniformity in heating at different levels sufficiently close for practical purposes, is obtained without materially complicating 25 the structure or operation of the kiln.

In a preferred form of construction of the improved kiln, the fuel used to heat the kiln is burned in combustion chambers located at the 30 opposite sides, and extending along the length, of a high temperature or heating section of the kiln, and the heating gases are passed into the goods space of the kiln partly through combustion chamber outlets adjacent the junction of 35 the heating and preheating sections of the kiln, and partly through outlets more remote from the preheating section. The last mentioned outlets are distributed along the lengths of the combustion chambers, and are arranged to deliver gases 40 into the goods space adjacent the bottom of the latter, so that the heating gases may pass upward in contact with the goods, and exert a greater heating effect on the goods adjacent the bottom of the goods space than upon the goods adjacent 45 the top of the latter. The heating gases thus introduced into the gas space are withdrawn in part, at least, from a portion of the preheating section located at a substantial distance from the heating section, so that there is a substantial longitudinal flow of heating gases through the preheating section of the goods space. My improved kiln includes adjustable dampers adjustable to regulate the relative amounts of heating gases 50 discharged through the different outlets from each combustion chamber.

When, as may sometimes be the case, the heating gases discharged from the combustion chambers and passing into the preheating section of the kiln heat up the goods passing through the preheating section of the kiln more rapidly than 5 is desirable, I may temper or suitably lower the temperature of the heating gas and air mixture coming into contact with the goods in the preheating section, by introducing cold atmospheric air into the kiln chamber at the junction of the 10 heating and preheating sections.

The various features of novelty which characterize the present invention are pointed out with particularity in the claims annexed to and forming a part of this specification. For a better understanding of the invention, however, its advantages, and specific objects attained with its use, reference should be had to the accompanying drawings and descriptive matter in which I have illustrated and described a preferred embodiment of the invention.

Of the drawings:

Figs. 1 and 1a are somewhat diagrammatic plan sections of adjacent longitudinal portions of a continuous tunnel kiln, constructed in accordance with the present invention;

Fig. 2 is a section, the left half of which is taken on the line 2—2 of Fig. 1, and the right half of which is taken on the line 2A—2A of Fig. 1a;

Fig. 3 is a section on the line 3—3 of Fig. 1;

Fig. 4 is a perspective view of a modified form of combustion chamber wall; and

Fig. 5 is a partial section on the line 5—5 of Fig. 3.

The kiln shown in Figs. 1 and 1a, comprises preheating, high temperature and cooling sections A', A² and A³, respectively, extending in the order stated between the entrance and exit ends of the kiln. The bottom or floor of the goods space of the kiln is a movable goods advancing hearth, formed, in the kiln shown, by the platforms C of kiln cars having wheels C' running on the track rails B. Each kiln car C, as shown, comprises a metallic understructure in which the car wheels C' are mounted, a refractory body portion C², girders C³ extending transversely of the car and supported on the body C² and supporting the goods supporting platform C of the car. The girders C³ are spaced away from one another to provide channels C⁴ extending horizontally through the car structure between the body C² and platform C. Openings C⁵ in the car platforms C permit of circulation of the kiln atmosphere between the goods space proper, of 55

which the car platforms C form the movable bottom wall, and the channels C⁴ which communicate at their ends with the spaces between the side edges of the platform C and the adjacent stationary portions of the kiln structure. As shown, the kiln cars are of the usual type, and for example, are like the cars shown in my prior Patent 1,521,216, granted Dec. 30, 1924. The car and kiln arrangement shown also follows the usual practice of the prior art in respect to the car and kiln carried means cooperating to maintain sand seals D, preventing gas flow at the sides of the cars, between the goods space of the kiln and the space beneath the car bodies.

At each side of the goods space, in, and extending for the full length of, the high temperature section A², and above the bench portion A⁴ of the kiln structure, is a combustion chamber E. At or adjacent its end remote from the entrance end 20 of the kiln, each combustion chamber is provided with a fluid fuel burner F, as shown an oil burner, and there may be one or more other burners F' opening to each combustion chamber at varying distances along its length. As shown in Fig. 1a, 25 each combustion chamber E is provided with two intermediate burners F'. The air for combustion may be air used in cooling the goods passing through the cooling zone A³, and be thereby pre-heated prior to its delivery to a flue space A⁵ 30 from each of which it passes to the adjacent combustion chamber E, at a rate regulated by adjustment of a damper IF. The details of the burner fuel and air supply provisions need not be further illustrated or described as they form no 35 part of the present invention.

The relative amounts of the products of combustion discharged from each combustion chamber E through the corresponding port G, and through the corresponding ports H, is regulated 40 and controlled by the adjustment of one or more dampers. For the purposes of such regulation, each combustion chamber will ordinarily be provided with a damper which, like the damper I shown, is immediately adjacent the corresponding port G, and is adjustable to variably throttle the latter. In the construction shown, the regulating effect of each damper I, is supplemented 45 by dampers IA, one located back of each of the forward burners F' and adjustable to variably throttle longitudinally flow through the corresponding combustion chamber, and by other dampers IB within the combustion chamber and adjustable to variably throttle flow through ports H distributed longitudinally of the combustion 50 chamber. As shown, openings A⁶ are formed in the side walls of the kiln, one back of each of the dampers IF, I and IA for the insertion of a hook bar or other implement for adjusting the adjacent damper, and other side wall openings A⁶ 55 are provided for the insertion of an implement for adjusting the dampers IB. The outer end of each opening A⁶ is normally closed, as by means of a stopper brick A⁶.

All of the products of combustion discharged 60 from the combustion chamber E through its ports G and H, flow longitudinally of the kiln into the preheating zone or section of the kiln goods space. From the latter, the spent, or nearly spent, heating gases are withdrawn through distributed ports A⁷ into flues A⁸ formed in the side walls of the kiln chamber and extending longitudinally of the preheating zone of the kiln. The distribution of inflow into each flue A⁸ through the different ports A⁷ may be controlled by the adjacent damper blocks A⁹. Each of the latter is accessible for

adjustment through a corresponding opening formed in the outer wall of the flue A⁸, and normally closed, as by means of a stopper block or brick A¹⁰. Heating gases are withdrawn from each flue, A⁸, through an uprising channel A¹¹, 5 communicating at its upper end with an offtake flue (not shown). The relative amounts of gas passing through the two flues A⁸ may be controlled by the adjustment of dampers A¹² in the vertical flues A¹¹. As those skilled in the art will 10 understand, the described preheating zone flue system described in this paragraph, is not novel herein, but, on the contrary, is of a type well known, and in extensive commercial use.

The wall between each combustion chamber 15 and the goods space of the kiln may take various forms. As shown in Figs. 1 and 2, the lower portion of each wall comprises a row of end to end ceramic bodies or partitions h separating horizontal channels extending transversely of the 20 kiln length, and constituting the above mentioned ports H. The upper portion of the wall is formed by a row of side by side tiles e, each having its lower end resting on the portion of the wall in which the ports H are formed. The tiles e are 25 inclined to the vertical so that the upper end of each tile is more distant than the lower end from the central plane of the kiln. The upper ends of the tiles e rest against the downwardly projecting shoulder ea from the roof of the kiln structure. The tiles e are formed with a plurality of 30 longitudinal channels e' each opening directly to the goods space at its upper end and opening to the goods space adjacent its lower end through a lateral port e².

As those skilled in the art will understand, the combustion chamber wall tiles e are of the type commonly used in forming the inner walls of the combustion chambers of "Dressler" tunnel kilns and serve two special purposes, namely, to augment and direct the convection current circulation of the kiln atmosphere, and to minimize the transfer of heat to the goods by radiation from the combustion chamber walls. Where more heat radiation to the goods from the combustion chamber walls, or a less pronounced convection circulation of the kiln atmosphere, is desirable, the tiles e of Figs. 1 and 2 may be replaced by the thin vertically corrugated wall plates eb, shown in Figs. 3 and 4. The tiles e and eb, may well be 45 formed of ceramic material such as silicon carbide which is not only suitably resistant to high temperatures, but has a relatively high heat conductivity at the temperatures to which the combustion chamber wall tiles are subjected.

The highly heated products of combustion which issue from the combustion chambers through the ports H enter the car channels C⁴ and pass from the latter through the openings C⁵ in the car platforms C into contact with the bottom portions of the goods stacks on the car platforms. The gases passing out of the combustion chambers through the ports H, thus have a greater heating effect on goods at a low goods space level, than on goods at a higher level. The goods heating action due to radiation from the tiles e, or eb, and that due to the convection current circulation of the kiln atmosphere, and particularly the portion of that circulation comprising the upflow through the channels e' in the tiles e, 70 collectively tend to a greater heating of the upper level goods than of the lower level goods. By simple adjustment of the various dampers I, IA, and IB, it is possible to regulate the low level heating effect of the gases discharged through the 75

ports H, as required to insure a suitably uniform heating action on the goods at different levels in the goods space, or to provide some definite difference between the temperatures at different levels.

As previously stated, atmospheric air may be passed into admixture with the heating gases which come into contact with the goods in the preheating section of the kiln. The air so admitted modifies the goods heating action in the preheating section of the kiln, and also prevents that action from being excessively rapid and the atmospheric air admitted also serves to make the atmosphere in the preheating section an oxidizing atmosphere, which is especially desirable in some ceramic firing operations. As shown, a channel A¹³ for the inflow of atmospheric air, is formed in the kiln structure at each side of the kiln chamber. As shown, each channel A¹³ opens into a lateral enlargement of the kiln chamber adjacent and at the outlet side of the corresponding damper I. The air thus introduced may be regulated in amount by the use of an obturator A¹⁴ of suitable size inserted in and partially obstructing the outer end of each channel A¹³.

The heating up action in the preheating section of the kiln may also be reduced by reducing the extent to which the heating gases discharged from the combustion chambers are allowed to come into contact with, and heat the goods moving through the preheating section of the kiln. The heating effect in the preheating section may thus be reduced by withdrawing a large portion of the heating gases from the portion of the goods space adjacent the junction of heating and preheating sections of the kiln, as by drawing the gases through the ports A⁷ nearest to the heating section A².

While in accordance with the provisions of the statutes, I have illustrated and described the best forms of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention, what I claim as new and desire to secure by Letters Patent, is:

1. In the operation of a continuous tunnel kiln including a preheating section adjacent one end, a cooling section adjacent the other end and an intermediate heating section and having combustion chambers at the sides of the heating section of a goods space through which goods are moved from one end of the kiln to the other, the method of regulating the relative temperatures to which the portions of the goods moving through the goods space at different levels are heated, which consist in passing heating gases from each combustion chamber at one end thereof, into the preheating section of the goods space, passing heating gases from the combustion chamber at points distributed along the length of its lower portion, into contact with the goods adjacent the bottom level of said space, and withdrawing heating gases from a portion of said preheating section displaced longitudinally of the kiln from said heating section.

2. In the operation of a continuous tunnel kiln including a preheating section adjacent one end, a cooling section adjacent the other end and an intermediate heating section and having com-

bustion chambers at the sides of the heating section of a goods space through which goods are moved from one end of the kiln to the other, the method of regulating the relative temperatures to which the portions of the goods moving through the goods space at different levels are heated, which consist in passing heating gases from each combustion chamber at one end thereof, into the preheating section of the goods space, passing heating gases from the combustion chamber at points distributed along the length of its lower portion into contact with the goods adjacent the bottom level of said space, withdrawing heating gases from a portion of said preheating section displaced longitudinally of the kiln from said heating section, and passing cold air into the goods space adjacent the junction of said heating and preheating sections.

3. In a continuous tunnel kiln having a goods space and means for moving goods through said space from one end of the kiln to the other, the combination with an elongated combustion chamber at each side of the goods space extending along a heating section of said space and having an end outlet adjacent one end of said section and having bottom outlets distributed along the length of the combustion chamber and communicating with and adapted to discharge heating gases into the goods space adjacent the bottom of the latter, means for withdrawing heating gases from a second section of the goods space, displaced longitudinally from the heating section, but adjacent the said end of the latter, burners opening into the combustion chambers, and damper means for regulating the relative amounts of heating gas discharged from each combustion chamber through its end and bottom outlets.

4. In a continuous tunnel kiln having a goods space and means for moving goods through said space from one end of the kiln to the other, the combination with an elongated combustion chamber at each side of the goods space extending along a heating section of said space and having outlets distributed along the length of the combustion chamber and communicating with and adapted to discharge heating gases into the goods space adjacent the bottom of the latter, other means for the discharge of heating gases from each combustion chamber, means for withdrawing heating gases from a second section of the goods space, displaced longitudinally from the heating section, but adjacent the said end of the latter, burners opening into the combustion chambers, and damper means for regulating the relative amounts of heating gas discharged from each combustion chamber through its bottom outlets and through its said other means.

5. In a continuous tunnel kiln having a goods space and means for moving goods through said space from one end of the kiln to the other, said means comprising a goods supporting platform and channels beneath said platform and ports in the platform through which said channels communicate with the goods space above the platform, the combination with an elongated combustion chamber at each side of the goods space extending along a heating section of said space and having an outlet adjacent one end of said section and having other outlets distributed along the length of the combustion chamber and communicating with and adapted to discharge heating gases into said channels, means for withdrawing heating gases from a second section of the goods space displaced longitudinally from the

heating section, but adjacent the said end of the latter, burners opening into the combustion chambers, and damper means for regulating the relative amounts of heating gas discharged from each combustion chamber through its ends and bottom outlets.

6. In a continuous tunnel kiln having preheating and heating sections arranged end to end and a goods space extending through said sections, the combination with elongated combustion chambers extending longitudinally of the heating section of the kiln at opposite sides of the goods space, each combustion chamber having an outlet to the goods space adjacent the junction of the preheating and heating sections and hav-

ing one or more other outlets and communicating with the goods space adjacent the bottom level of the latter, and at a distance from said junction, means for effecting combustion in said goods space, means for withdrawing heating gases from the kiln in part, at least, from a portion of the goods space at a distance from said junction, adjustable damper means for regulating the relative amounts of heating gases passing through the first mentioned outlet and passing through 10 said other outlet or outlets of each combustion chamber, and means for supplying cold air to the goods space adjacent said junction.

PHILIP D'HUC DRESSLER. 15
